UNITED STATES PATENT OFFICE.

THOMAS P. LARKIN, OF BROCKTON, MASSACHUSETTS.

REINFORCED LAST.

1,247,550.

Specification of Letters Patent. Patented Nov. 20, 1917.

Application filed April 13, 1917. Serial No. 161,908.

To all whom it may concern:

Be it known that I, THOMAS P. LARKIN, a citizen of the United States, and resident of Brockton, in the county of Plymouth and 5 State of Massachusetts, have invented an Improvement in Reinforced Lasts, of which the following description, in connection with the accompanying drawings, is a specification, like letters on the drawings representing 10 like parts.

My present invention is a reinforcing device to strengthen the portion of a last such as at the toe, and the reinforced last itself, as an improved article of manufacture.

15 My invention applies to any style, shape or size last, and is equally advantageous for use in connection with a solid or block last, a hinge last, or other separable type, tree feet, followers, etc., and can be employed on children's, men's or women's lasts. In the use of any of the types of lasts above mentioned, certain portions are particularly liable to damage and injury during numerous shoe making processes and machine operations to which the last is subjected. One 20 of these portions particularly liable to damage is at the toe, where the wood of the last is narrowed, usually thin and fined down, and frequently considerably pointed, also 25 running with the grain of the wood from which the last is made. Consequently the toe wipers of the lasting machines ordinarily employed, break or damage the toe portions, particularly at the edge of the toe and bottom 30 of the last, so that the wood constantly breaks away and the last is quickly ruined. In the manufacture of the welt type of shoes, it is impossible to cover the entire last bottom with metal, since the lasting tacks must 35 be free to take hold of the wood of the last. Therefore, considerable difficulty has been experienced in applying reinforcing plates of any kind to the toe portion of lasts intended for welt shoe work. A further difficulty 40 has been that the wood at the toe portion is so thin and narrow that it was difficult, if not impractical, to attach any usual type of thin plates to protect the toe portion, against damage by the wipers as above 45 noted. My invention relates to an improvement in this feature, enabling a cheap, economical and efficient reinforcing device which has anchoring means remote from the toe portion and lodged in the solid, firm,

inner wood portions of the last, to be applied. A further feature consists in the application of such reinforcement at the toe, as a small light plate, which will cover only a small area of the last bottom, and therefore will not interfere with the lasting 55 tacks entering the wooden part of the last at either side of the toe portion.

The importance of my invention will be appreciated when it is realized that, in welt shoe manufacture, the last is alternately 60 wet and dried from the moist insoles, box toe construction, and the like. It is now customary to steam the box toe, which softens the wood just before lasting, when the greatest strain is applied, thus still further calling upon the last for considerable 65 "give and take" during the alternate wet and dry stages. It is important, therefore, that a reinforcing plate should be closely 70 and firmly connected to the toe portion, and, as above noted, it is impossible to affix such a plate satisfactory by the usual screws or 75 nails because the wood at the toe is cut away to a very great extent. I am aware that an attempt has been made to reinforce toes 80 by fiber strips, and also that relatively long and correspondingly heavy and expensive iron plates have been applied to the toe portion of a last running back considerably over 85 the forepart in order to admit retaining screws for said plates to be inserted in the solid wooden portion of the forepart, but all these prior efforts have been unsatisfactory, the long and heavy plates, particularly involving expense, preventing the lasting 90 tacks from entering the wood and because the retaining screws were so far back from the point of the toe as to permit a separation of the reinforcing plate from the wood, especially when the wood shrinks, and often 95 tearing the lining during the action of the toe wipers already explained.

My invention obviates all these prior difficulties and furthermore enables an inexpensive, economical, strong, permanent and 100 durable reinforcement for the extreme tip portion of the toe to be quickly applied to any wooden last.

Referring to the drawings illustrating a preferred embodiment of the invention, 105

Figure 1 is a side view of my reinforced last;

Fig. 2 is an enlarged view of the toe por-

tion partly broken away, illustrating the application of the metal reinforcement and its retaining means;

Fig. 3 is a plan view of the reinforced toe portion as shown in Fig. 2;

Fig. 4 is an enlarged plan view of the reinforcing plate; and

Fig. 5 is a side view of the plate.

As above explained, my reinforced last 10 may be either a solid, hinged, or other type of last, that herein illustrated being a usual type of hinge last, comprising a forepart 1 and heel part 2. At the extreme toe portion, where the wood of the last is relatively thin 15 and pointed, I apply my reinforcing plate 3. I first provide a relatively small recess 4 across the toe portion of the last of equal depth to the thickness of the metal in the plate 3, leaving a straight shoulder 5 transversely of the last. I then bore obliquely with relation to the surface 5 two recesses 6 and 7 respectively. These recesses are of sufficient depth to extend into the broader and firmer wooden portions of the forepart 20 and being at an angle present no tendency to split the wood in the toe portion, which latter is usually along the line of the grain, owing to the general last construction with regard to the grain of the wood in the last. 25 The plate 3 is provided with rearwardly and obliquely extending prongs 8 and 9; extending from the plate 3 corresponding to that of the bored recesses 6 and 7, and preferably of slightly greater diameter than the bore of said recesses. The plate 3 is 30 then applied to the recess 4 with the rearwardly and obliquely extending prongs 8 and 9 driven into the corresponding recesses 6 and 7, thus affording a firm, solid, holding attachment for the plate 3. Furthermore, the two small recesses which are filled 35 with a driving fit by the prongs 8 and 9, in no way weaken the toe portion of the last, but actually constitute a reinforcement thereto, solidifying the wood between the prongs and taking up in a solid manner all strains and stresses to which the toe portion of the last is subjected. My reinforcing plate, thus secured, gives ample space 40 for the usual lasting tacks right up to the toe portion, it being customary to wire the toe portion from a short distance back from either side, suitable anchor tacks being employed for this purpose, which may be firmly anchored in the wood of the last 45 without interference from the tip plate 3 or the prongs 8 and 9. The latter are sunk in sufficiently deep so that even should a lasting tack, as indicated at 10, Fig. 2, be 50 driven into the last, the plate or prongs would not interfere therewith while giving the tack ample hold upon the wood in the last bottom. While the retaining prongs 8 and 9 are quite sufficient to retain the 55 small and light reinforcing plate 3 in its

position and the angular construction insures the firm seating and holding of the plate 3 in its position on the toe, I also prefer to make the plate 3 with a central aperture 11 through which a short screw 12 is threaded into the toe of the last for the purpose of preventing withdrawal of the prongs 8 and 9. This screw 12 does not need to extend any substantial distance into the toe portion, being in the nature of a retaining pin or the like to prevent loosening of the toe plate by withdrawal of the retaining prongs, as above explained. It will also be appreciated that my reinforcing plate 3 may be curved to fit the shoe bottom curve in the last. Furthermore, I contemplate the making or stamping of this bottom plate 3 with a sufficient area to fit a large range of toe styles. By having the toe plate 3 of greater area than the majority of the toes of lasts, the plate can be applied and then trimmed down by shears or files to exact contour with the style of toe to which it is fitted. As illustrated in Fig. 2, the plate 3 therein shown could readily be trimmed down to the contour and style of toe indicated by the dotted line at 15, or any other contour within the range of the plate. In this manner, but one or two standard sizes of toe plates will be suitable for fitting to substantially all modern styles of toes.

It will be appreciated that any desirable manner or method of forming the recess 4 and the angular boring 6 and 7, can be employed, it being customary to use a guide for the last or for the jigs forming such recess and the drills making the bores, which involves but slight expense and short time. My improved reinforced last is found to stand up perfectly under the strain of the lasting wipers and other work in the manufacture of welt shoes. The extreme thin toe portions are reinforced and strengthened, and are rigidly and firmly retained in the recesses 4 through the oblique prongs 8 and 9, giving substantially a truss effect thereto, and resisting displacement in all directions. It will also be appreciated that I may apply such reinforcements to other parts of the last, such as the cone or heel, should the latter be deemed desirable, although it is the extreme toe portions, as above explained, which are subjected to the undue and extreme strains of lasting wipers and yet must be left free for the lasting tacks, and withstand the wetting and drying of the last, toe steaming of the box, and similarly extraordinary stresses to which my last is peculiarly adapted.

My invention is further described and defined in the form of claims as follows:

1. A reinforced last of the kind described, comprising a wooden last recessed at the point to be reinforced, a metallic plate 130

adapted to fit said recess, and attaching means for said plate extending obliquely from said plate and recess into the solid inner parts of the last remote from the portion 5 reinforced.

2. A reinforced last of the kind described, comprising a wooden last, having a recess at the toe portion of said last across the bottom, and having a shoulder defining said 10 recess, and a metallic reinforcing plate adapted to fit within said recess flush with said shoulder and conforming to the contour of the toe of the last, said last having a plurality of obliquely extending openings 15 from said recess and the metallic plate having a corresponding plurality of angularly extending prongs, fitting said openings and rigidly uniting the plate and last.

3. A reinforced last having a bottom plate 20 at the toe portion to resist the breaking action of lasting machine wipers, comprising a thin metallic plate fitted across the toe por-

tion of the last and a plurality of rearwardly and obliquely extending prongs driven within the inner solid parts of the 25 last at a sufficient depth to avoid interference with lasting tacks, and additional means to prevent the displacement of said plate and loosening of the attaching prongs.

4. A reinforcing plate for a wooden last, 30 consisting in a thin metallic member curved transversely and with appropriate contour to fit the portion of the last reinforced, said plate having a plurality of attaching prongs extending rearwardly and obliquely to penetrate 35 the wooden portion of the last remote from the part reinforced by the plate.

In testimony whereof, I have signed my name to this specification, in the presence of two subscribing witnesses.

THOMAS P. LARKIN.
